(57) **CLAIM**

The ornamental design for a steak knife, as shown and described.

DESCRIPTION

FIG. 1 is a side elevational view of a steak knife having a wood grain handle, a bronze tang, and bronze rivets, the other side view being a mirror image thereof;

FIG. 2 is a top plan view thereof;

FIG. 3 is a bottom plan view thereof;

FIG. 4 is a front elevational view thereof; and,

FIG. 5 is an end elevational view thereof.
